UNITED STATES PATENT OFFICE.

WILLIAM J. DE WITT, OF AUBURN, NEW YORK, ASSIGNOR TO THE SHOE FORM CO.
INC., OF AUBURN, NEW YORK, A CORPORATION OF NEW YORK.

EXPANSIBLE SHOE FORM.

Application filed July 27, 1926. Serial No. 125,172.

This invention pertains to expandible forms or trees designed to keep footwear plumped out and free from wrinkles while on exhibition or during intervals between 5 periods of use, and for specific illustration is herein disclosed as comprising a resilient hollow thin-walled shell such as may conveniently be made of sheet celluloid or some similar material, although in its broader 10 aspects it is not necessarily limited to forms of this particular type.

Expandible forms or trees, as compared with non-expandible forms, have certain well recognized advantages. For example, they 15 may be introduced into the boot or shoe more easily than the non-expandible form; they exert an outward pressure tending not only to prevent wrinkles but also to eliminate wrinkles previously formed; and they may, 20 if desired, be so designed as actually to stretch the shoe.

While such expandible forms have these and possibly other advantages they usually 25 possess at least one defect which, so far as I am aware, has not been adequately remedied, previously to the present invention. This defect arises from the mechanical difficulty of making a form which will at all 30 times and at all stages of expansion or contraction present for contact with the interior of the shoe a surface which is unbroken and continuous and which exerts substantially equal pressure at opposite sides of the shoe upper irrespective of the relative amounts 35 to which such opposite sides may yield.

The principal object of the present invention is to provide an expandible form having a smooth exterior contour and which is adapted to exert a lateral pressure of substantially equal amounts against opposite sides of the shoe regardless of the relative 40 yieldability of the upper at various points, or, in other words, to provide a form which expands outwardly to amounts respectively 45 proportionate in inverse ratio to the resistances which it encounters at various points.

In the accompanying drawings certain desirable embodiments of the invention have been illustrated by way of example, and 50 in the drawings,

Fig. 1 is a bottom plan view of one embodiment of the invention showing the form removed from the shoe;

Fig. 2 is a vertical longitudinal section,

of more or less diagrammatic character, illustrating a strap pump having the form of Fig. 1 disposed therein;

Fig. 3 is a view similar to Fig. 1 but illustrating a modified construction;

Fig. 4 is a view similar to Fig. 2 but showing the form of Fig. 3 fitted within the shoe;

Fig. 5 is a view similar to Fig. 1 but showing a form of further modified construction;

Fig. 6 is a view similar to Fig. 2 but illustrating the form of Fig. 5;

Fig. 7 is a view similar to Fig. 3 but illustrating a further modification; and

Fig. 8 is a view similar to Fig. 4 but showing the form of Fig. 7 disposed within the shoe.

Referring particularly to Figs. 1 and 2, the numeral 1 designates a hollow thin-walled member or shell adapted to fit into the toe portion of a boot or shoe. This hollow member 1 may, if desired, be made of sheet celluloid or similar material by a process such as is disclosed in my Patent No. 1,585,284, dated May 18, 1926, although so far as the present invention is concerned, the mode of preparation of this hollow thin-walled resilient member is immaterial.

The shell 1 should be shaped so as to conform fairly closely to the interior surface of the shoe with which it is to be used, although in its normal unexpanded condition, it should slip easily into the shoe. In Fig. 2 the shoe or pump is shown as comprising the upper 2, the sole at 3, the heel 4, and the rear or counter portion 5.

The hollow thin-walled member or shell 1 is furnished with a pair of substantially rigid spreader bars or links 7 and 8 which cross each other intermediate their ends as indicated at 9 in Fig. 1. The end 11 of the link 7 is pivotally secured in any desired manner to one side of the member 1. Preferably as here shown the member 1 has an inturned marginal flange 6 at its lower edge which is adapted to rest on the inner surface of the shoe sole, and if such flange be provided, the end 11 of the link 7 may, as here shown, be pivotally attached to this flange, the opposite end 10 of the link resting freely upon the upper surface of the flange. The spreader link 8 is likewise pivotally attached at its end 12 to the member 1.

at a point opposite to the pivot 11, the other end 13 of the link 8 being free to move along the flange 6.

Preferably the intermediate portions of 5 the spreader links 7 and 8 are bowed upwardly as indicated at 14 to accommodate a loop member 15 which loosely embraces the two links at their crossing point 9. This loop member is sufficiently loose to permit 10 endwise movement of the links 7 and 8, it being noted that the crossing of these links is not a fixed and definite point but may vary in accordance with the relative endwise shifting of the two links.

15 The loop 15 is attached to the forward end of a resilient bar 16. As here shown, this loop 15 is integral with the bar, being formed by bending or coiling the bar, and the opposite end of the bar 16 is preferably 20 provided with a loop 17 providing a smooth surface adapted to engage the inner surface of the counter portion of the shoe. Preferably the bar 16 is bent or bowed slightly, and to introduce the form into the shoe, with 25 the member 1 in the toe portion of the shoe and the member 17 engaging the counter, this bending or bowing of the link must be increased. This bending of the bar 16 provides the necessary spring tension for 30 forcing the member 1 firmly into the toe portion of the shoe and produces a force acting forwardly through loop 15 tending to move the crossing point of the links forwardly and thus to bring the links more 35 nearly into parallel relation. Obviously any such movement of the links 7 and 8 tends to expand the member 1 laterally, but since the links 7 and 8 are free to move endwise relatively to each other, the points of connection 40 of the links to the member 1 do not necessarily move in any predetermined path, but on the other hand move in inverse ratio to the resistance met with at these points. The result of this arrangement is that substantially 45 equal pressures are exerted at opposite sides of the shoe and at the front and rear portions thereof so that fullness or wrinkles in the upper occurring at any given point are plumped out in the desired manner without unduly straining other parts of 50 the upper.

By properly proportioning the parts and designing the bar 16 the requisite expansive 55 pressure may be provided for a shoe of any given size. When the form is to be withdrawn it is merely necessary to spring the bar 16 to permit the end 17 thereof to escape over the upper edge of the counter, whereupon the hollow member 1 tends to resume its normal dimensions, thus permitting it to 60 be withdrawn from the shoe without difficulty.

In the modified construction shown in 65 Figs. 3 and 4 the hollow member 18 is of substantially the same type as the member

1 previously described. This hollow member has the marginal inturned flange 19 and is provided with a pair of crossed spreader links 20 and 21. The ends 22 and 24 respectively of these links are pivotally connected 70 to the flange 19 at opposite sides of the form.

In this arrangement, in addition to the spreader links, I provide a toggle linkage comprising the link members 26 and 27 which are pivotally united at 28 to form a 75 knuckle joint. The outer extremities of the links 26 and 27 are pivotally secured at 25 and 23 respectively to the rear ends of the links 21 and 20.

Preferably the joint uniting the links 26 80 and 27 is provided by bending each link to form an eye, as indicated at 29 and 30 in Fig. 4 and passing a loop 31 through these eyes so as to unite the links. Preferably this loop member 31 is integral with the forward end of the spring bar 32. This bar is generally similar in construction and function to the bar 16 previously described, and at its rear end is furnished with a loop 33 for engagement with the inner surface of the 90 shoe counter.

Preferably the member 32 is provided with a forward extension 34 (Fig. 3) having an elongate loop 35, which loosely embraces the links 20 and 21 at their crossing 95 point.

With this arrangement, when the form is inserted within the shoe, the pressure exerted by the spring bar 35 forces the toggle linkage 36 and 37 forwardly into the dotted line 100 position of Fig. 3. This movement of the toggle linkage forces the rear ends of the spreader links 20 and 21 forwardly and outwardly, but as the spreader links are not connected at their crossing point, their pressures are distributed in the same manner as above described with respect to the device shown in Fig. 1. However, in this arrangement, the toggle linkage in moving forwardly, passes the center line defined by the pivots 23 and 25 so that it positively locks the form in expanded condition. When the toggle linkage has assumed the extreme forward position desired, the rear end of the loop 35 engages the spreader links at their 110 crossing point and this prevents further movement of the toggle linkage.

In the arrangement shown in Figs. 5 and 6 the hollow member 1^a is substantially like the member 1 shown in Fig. 1. This hollow member is provided with the spreader links 7^a and 8^a secured at their opposite ends 11^a and 12^a, to the opposite sides of the member 1^a respectively. The loop 15^a embraces these crossing spreader links at their crossing points, such loop being carried by 125 or forming a part of the spring bar 16^a.

In this modification the bar 16^a extends rearwardly and is provided with a hairpin bend 36 from which point it extends for 130

wardly and upwardly to the point 37 and thence downwardly to provide the supporting member 38, preferably terminating in the closed loop 39. This arrangement provides a support for the upper portion of the vamp 40 of the shoe, and if as shown in Fig. 6 the shoe has straps or equivalent devices 41, this supporting member 38 also holds these straps in proper position.

In Figs. 7 and 8 the numeral 18^a designates a hollow member similar to the member 18 in Figs. 3 and 4, such member being provided with the crossing spreader links 20^a and 21^a connected to the hollow member at the points 22^a and 24^a, respectively. This arrangement is also provided with the toggle linkage 26^a, 27^a, similar to that shown in Fig. 3 and with the stop member 35^a. In place of the spring bar 32 of Fig. 4, a bar 32^a is provided which extends rearwardly to the hairpin bend 36^a, thence forwardly to the point 37^a, and then downwardly to provide the supporting member 38^a terminating at 39^a. This member 38^a supports the upper part of the vamp of the shoe in the same manner as the member 38 of Fig. 6.

In all of the several modifications illustrated the provision of the crossing spreader links which are free to move endwise relative to each other, assures the proper application of pressure to the various parts of the shoe upper without straining the upper or unduly stretching it at certain points as is the common result from the employment of trees or forms in which the opposite sides are constrained to move in definite relation to each other.

While the form herein shown is designed more particularly for plumping out the toe portion of a shoe, I wish it to be understood that the principle underlying the invention is not restricted to a form of this particular type, but may well be embodied in forms adapted to fill a greater part of or even the entire shoe. I further contemplate that although for best results the hollow member 1 is desirable, since it provides a smoothly continuous surface for distributing the pressure of the spreader links, it may be possible under some circumstances to dispense with this hollow member 1 and to provide the spreader links at their outer ends with independent contact surfaces for engagement with the inner walls of the shoe.

While a pair of spreader links has been shown, I contemplate that a greater number of such crossing spreader links may be employed or that several pairs of such links may be situated at various parts of the form provided the form be of greater dimensions than that here shown.

I claim:

1. An expandible shoe form comprising a thin walled shell adapted to enter a shoe, said shell having a smoothly continuous outer surface engageable with the inner surface of a shoe upper and means for forcing opposite sides of the shell outwardly to amounts respectively proportionate, in inverse ratio, to the resistances which they encounter.
2. An expandible shoe form for insertion within a shoe, said form comprising a hollow thin walled shell of celluloid having a smoothly continuous outer surface, and means for exerting substantially equal pressures at opposite sides of the shell irrespective of the relative amounts to which such opposite sides yield.
3. An expandible shoe form comprising a hollow resilient shell having a smoothly continuous outer surface shaped to conform to the interior surface of a shoe upper, and means for applying substantially equal outwardly directed force at a plurality of spaced points at each side of said shell.
4. An expandible shoe form comprising a plurality of spreader links, each link having its ends disposed at opposite sides of the form respectively, the several links crossing each other intermediate their ends, and pressure applying means loosely engaging the several links at their crossing point.
5. An expandible shoe form comprising a plurality of spreader links, each link having its ends disposed at opposite sides of the form respectively, the several links crossing each other intermediate their ends, and a pressure applying member having a loop loosely embracing the several links at their crossing point.
6. An expandible shoe form comprising a plurality of spreader links, each link having its ends disposed at opposite sides of the form respectively, the several links crossing each other intermediate their ends, and a resilient member having a loop at one end loosely embracing the several links at their crossing point, said resilient member having a surface engageable with the rear end of the shoe within which the form is placed.
7. An expandible shoe form comprising a plurality of spreader links, each link having its ends disposed at opposite sides of the form, respectively, the several links crossing each other intermediate their ends, but being free to move endwise relatively to each other, and means for applying force to the links in a direction such as to tend to move their rear ends forwardly.
8. An expandible shoe form comprising a plurality of spreader links, each link having its ends disposed at opposite sides of the form respectively, the several links crossing each other intermediate their ends, but being free to move endwise relatively to each other, and means for moving the rear ends of the links forwardly and for locking them in their forward position.
9. An expandible shoe form comprising a

- plurality of spreader links, each link having its ends disposed at opposite sides of the form respectively, the several links crossing each other intermediate their ends but being free to move endwise relatively to each other, and means including a spring and a toggle for moving the links more nearly into parallelism and for locking them in such position.
10. An expandible shoe form comprising a plurality of spreader links, each link having its ends disposed at opposite sides of the form respectively, the several links crossing each other intermediate their ends but being free to move endwise relatively to each other, a toggle comprising a pair of pivotally connected links each having its free end connected to the end of one of said spreader links, said toggle links normally converging toward the rear of the form, and a pressure applying spring connected to the junction point of the toggle links and tending to move the junction point of said links forwardly.
15. An expandible shoe form comprising a thin walled shell shaped to fit within a shoe, said shell having an inwardly directed flange at its lower edge, a plurality of spreader links, each link having one of its ends pivotally connected to the flange, said links crossing each other intermediate their ends, the links being free to move endwise relatively to each other, and an elongate resilient pressure applying device having a loop loosely embracing the spreader links at the crossing point and abutting against the inner surface of the rear portion of the shoe within which the form is placed.
20. An expandible shoe form comprising a thin resilient shell adapted to fit within a shoe, a pair of spreader links, each link having one of its ends pivotally attached to the side of the shell, the links crossing intermediate their ends but being free to move endwise relatively to one another, a toggle linkage having its ends pivotally connected to the shell adjacent to the rear ends of the spreader links, a resilient member adapted to abut against the inner surface of the rear end of a shoe in which the form is placed, said resilient member exerting force in a forward direction on the joint of the toggle linkage, and an extension of said resilient member engageable with the spreader links adjacent to their crossing point to limit forward movement of the toggle.
25. An expandible shoe form comprising a thin walled shell for insertion within a shoe upper, a plurality of links, each link having one of its ends pivotally united to one side of the shell, said links crossing each other intermediate their ends, a loop loosely embracing the several links, and resilient means adapted to move the loop forwardly toward the toe of the shell.
30. An expandible shoe form comprising a thin shell adapted to fit within a shoe, a pair of spreader links, each link having one of its ends pivotally attached to the side of the shell, the links crossing intermediate their ends but being free to move endwise relatively to one another, a toggle linkage having its ends pivotally connected to the shell adjacent to the rear ends of the spreader links, a bowed spring rod having a part adapted to abut the inner surface of the counter portion of a shoe and connected at its forward part to the knuckle of the toggle, said rod having a forward extension provided with an elongate loop embracing the spreader links adjacent to their point of crossing.
35. An expandible shoe form comprising a thin walled shell for insertion within a shoe upper, a plurality of links, each link having one of its ends pivotally connected to the side of the shell, said links crossing each other intermediate their ends, the links being free to move endwise relatively to each other, and means for applying force to the several links tending to move them into parallelism.
40. An expandible shoe form comprising a thin walled shell for insertion within a shoe upper, a plurality of links, each link having one of its ends pivotally connected to the side of the shell, said links crossing each other intermediate their ends but being free to move endwise relatively to one another, and a device for applying force to said spreader links whereby to move them more nearly into parallelism, said device comprising a spring having a part adapted to support the central upper part of the vamp of a shoe in which the form is placed.
45. An expandible shoe form comprising a thin resilient shell adapted to fit within a shoe, a pair of spreader links, each attached, respectively, to one side of the shell, the links crossing intermediate their ends but being free to move endwise relatively to one another, and a device for applying force to said spreader links whereby to move them more nearly into parallelism, said device comprising a spring having a part adapted to support the central upper part of the vamp of a shoe in which the form is placed.
50. An expandible shoe form comprising a thin walled shell for insertion within a shoe upper, a plurality of links, each link having one of its ends pivotally connected to the side of the shell, said links crossing each other intermediate their ends, the links being free to move endwise relatively to each other, and a spring device engageable with the rear part of a shoe in which the form is inserted, said spring device applying for-

a thin resilient shell adapted to fit within a point, the intermediate portion of the spring
shoe, a pair of spreader links, each link having one of its ends pivotally attached to the
side of the shell, the links crossing intermediate their ends but being free to move
5 endwise relatively to one another, and a device for forcing the rear ends of the
spreader links forwardly, said device comprising an elongate spring having a loop at
10 one end embracing the links at their crossing

abutting the inner surface of the counter of a shoe in which the form is placed, the other end portion of the spring extending forwardly and constituting a support for the 15 forward upper portions of the shoe.

Signed by me at Auburn, N. Y. this 22nd
day of July 1926.

WILLIAM J. DE WITT.
